Victoria Morton
Inventor

By her Attorney James P. Duhamel.

UNITED STATES PATENT OFFICE.

VICTORIA MORTON, OF NEW YORK, N. Y.

GARBAGE-PAIL.

1,218,574.

Specification of Letters Patent. Patented Mar. 6, 1917.

Application filed August 26, 1916. Serial No. 117,020.

To all whom it may concern:

Be it known that I, VICTORIA MORTON, citizen of the United States, and resident of New York, in the county of New York and State of New York, have invented certain new and useful Improvements in Garbage-Pails, of which the following is a specification.

This invention relates to garbage pails and 10 consists of a substantial sheet metal pail with a lid and handle and inclosing a basket of wire also having handles and somewhat smaller than the pail and adapted to contain a bag or receptacle of water proof 15 paper, the object of the invention being to deposit the garbage in the bag and to support the latter in the basket so that in case of leakage of liquid through the bag it will not cause the paper to adhere to the sides of 20 the container and the pail will not become foul from material left therein, as will be more fully described in the following specification, set forth in the claims and illustrated in the drawings, wherein:

25 Figure 1 is a cross sectional view of the improved pail.

Fig. 2 is an elevation of the wire basket.

Fig. 3 is an elevation of the bag.

30 Fig. 4 is a plan view of the device with the lid removed.

In garbage pails heretofore used great difficulty has been experienced in keeping the same clean on account of the liability of small bits of the garbage accumulating in the 35 corners of the pail and of the trouble necessary to clean the same. Linings have been provided for the pails but as the least leakage of the material and particularly the liquid will cause the paper to adhere to the 40 sides of the pail it soon becomes an undesirable feature and is discarded.

In the present invention means are adapted to relieve the lining of this danger of sticking to the pail by inclosing it in a 45 wire basket and providing space between the basket and the inside of the pail so that the circulation of air around the basket will

tend to dry the moisture in the garbage and prevent the same from draining into the 50 pail.

The paper bag containing the garbage may then be removed and with its contents thrown away or burned, and the pail kept pure and odorless.

In the drawings is shown a pail 5 of the 55 common type and having a cover 6 and a handle 7, and within the pail is located a basket 8 of wire mesh of sufficient texture to properly support the bag and having a 60 binder 9 at its upper edge to strengthen the 65 same, and handles 10 are provided to manipulate the basket.

Within the basket is carried a bag 11 of 70 water proof paper and having an overturned upper edge 12 to fit over the binder 65 9. This edge 12 is in some instances sufficiently stiff to hold the bag from contact with the basket at any point but if the amount of garbage is very great the bag 75 will be supported by the bottom of the basket leaving air space beneath the same.

When garbage is placed in the bag the latter is practically held in suspension and may be dried while inclosed and be in condition for burning in a few hours, or finally 75 disposed of in the dry state, the chances for the leakage and accumulation of the liquid garbage being very slight and if any should find its way into the pail it could be easily 80 washed out.

The pail when closed with its lid may be kept in an apartment or kitchen and will give off no offensive odors and the bag is cheap enough to throw away with its contents when desired, leaving the basket and 85 pail in a wholesome condition and ready to receive a new bag for more garbage.

It is obvious that the device may be otherwise arranged or modified without departing from the essential features above described or from the scope of the appended 90 claims.

What I claim as new is:

1. In a garbage pail, the combination

with the pail, of a basket adapted to be contained therein, and a water-proof bag for the basket.

2. In a garbage pail, the combination
5 with the pail, of a wire basket smaller than the pail and adapted to be contained therein, and a water-proof bag for the basket and adapted to contain the garbage.

3. In a garbage pail, the combination

with a pail having a top and a handle, of a 10 wire basket of less diameter than and adapted to be located within the pail, and a water-proof paper bag to fit within the basket.

Signed at New York, in the county of New York, and State of New York this 25th day 15 of August, A. D. 1916.

VICTORIA MORTON.
